SURFACE DRAINS

Martin A. Sisk, 1010 House Bldg., Pittsburgh 22, Pa.;
Lulu E. Sisk executrix of said Martin A. Sisk, deceased

Filed Feb. 20, 1956, Ser. No. 566,698

3 Claims. (Cl. 210—166)

My invention relates to surface drains, access boxes or the like, for use in the floors of shower bath enclosures, roadways, decks of ships, floors and roofs of buildings, and the like, to provide debris-excluding protection at the inlets of drain openings or pipes. The structure of the invention will also find utility as a guard for pipes and openings of any sort in which liquid is received, and in the operation of which it is desirable to exclude solids of a size that might clog the opening, or the pipe leading therefrom.

In general, an outlet or floor drain of the type in mind consists in a cup-shaped body that is installed within or below the floor or other structure whose surface is to be drained, and the inlet of the body is covered by a removable top or grate. The upper face of the grate usually lies flush with the surface to be drained. The body of the drain forms a belled terminus at the end of a drain pipe laid beneath or within the structure whose surface is to be drained.

In the usual prior structures the grate consists in a perforate cover of metal which rests at its periphery in a rabbeted seat formed in the rim of the body of the drain, and most of the water entering the drain does so through holes or openings in the cover or grate located inwardly from the rim of the drain body, with the result that the flowing water does not completely flush the inner surface of the side wall of the drain body. Consequently, debris carried by the waste water tends to accumulate on such surface of the drain body, especially just below the grate, and between the seat in the drain body and the edge of the grate. The accumulated debris over a period of time decomposes, creating foul odors and unsanitary conditions. In order to cleanse such drains, it is necessary to remove the grate and scrub or scrape away the accumulations—manifestly an unpleasant task. An important feature of this invention resides in the elimination of these objectionable conditions in drains embodying the structural refinements defined in the appended claims.

My present invention comprises a renewable rim that is particularly though not exclusively adapted for use in a drain structure which has a peripheral slot whose outer edge is vertically aligned, or substantially so, with the inner surface of the drain body. This slot is effective throughout the periphery of the drain body inlet, and the internal surfaces of the drain body extend from this slot downwardly to the drain outlet, or to the inlet of the drain pipe on which the drain body is mounted, affording a clear unrestricted down-sweep for the flow of the draining water. No objectionable ledges, channels, or crevices are present in the structure, on which or in which debris may accumulate.

The drain body may be formed of two telescopically assembled body portions that are relatively adjustable in vertical direction, whereby the effective height of the body may be varied as need be in certain installations. Preferably, if not essentially, the two body portions are united in a threaded joint, with the effect that the said adjust-

2

ment may be obtained by the relative rotation of the body portions.

In the accompanying drawings:

Fig. 1 is a view in plan of a drain structure of the sort 5 in which the invention may be embodied;

Fig. 2 is a view of the drain structure in vertical section, on the plane indicated at II—II in Fig. 1;

Fig. 3 is a fragmentary view, showing in vertical section and on larger scale how a structure of the invention 10 is embodied in the drain structure;

Fig. 4 is a fragmentary view, showing in vertical section a drain structure that incorporates a modified structure of the invention; and

Figs. 5 and 6 are fragmentary views, illustrating respectively in plan and in vertical section a strainer type surface drain in which the invention is embodied.

Referring to Figs. 1 and 2 of the drawings the drain body will be seen to comprise two castings 3 and 4 united in a threaded engagement 5. The castings may be rough 20 castings of a relatively inexpensive material such as iron. The upper body or collar portion 4 of the body is provided with a peripheral rim 6 that defines the inlet of the drain body, across which a grate 7 is positioned, in this case with the top of the grate flush with the surface 8 of 25 the floor to be drained. Extending downwardly from the rim 6 the side wall of the two-part drain body comprises a vertical succession of smooth annular surfaces e, f, g, h, i, and j, the latter surface (j) sloping downwardly and inwardly to an opening—in this case a threaded opening k— 30 which receives the terminal of the drain pipe (not shown), for conducting the drainage liquid to a sewer or other point of disposal. The threaded union 5 of the two parts of the drain body permits the upper body portion 4 to be vertically adjusted after the lower body portion 3 has been 35 affixed on the end of the drain pipe, whereby the top of the rim 6 may be made flush with the surface 8 to be drained.

While the inlet of the drain body is herein shown to be circular in plan, it will be understood that the form of 40 such inlet may be square, octagonal, or of other contour.

The internal side wall of the two-part drain body, extending downwardly from the rim 6 in a substantially continuous series of smooth surface areas (e to j) that fair with one another, provides a down-sweep that is unobstructed, having no recesses or ledges in which, or upon 45 which, drainage water, or sediment, or debris may accumulate. Cooperating with this particular form of the internal surface of the drain body is a slot 9 formed between the grate body portion and the rim 6 of the drain body inlet.

The lower portion of the drain body has a radially extending horizontal flange 10 upon which the usual sub-floor membrane or flashing of lead or tar paper (not shown) is secured. This is a conventional detail of construction, and for present purposes it need only be remarked that any water seeping from the floor surface 8 downwardly between the drain body and the adjacent body of the floor is caught on the membrane and drained through weep holes 11 into the drain body.

The grate or perforate top 7 of the drain structure is 50 in this case of general plate or disk-like form, comprising an annular portion whose outer periphery is indicated at 12. Within such annular portion spaced cross-bars or bearer-bars 13 form the open-work structure of the grate, through which drainage liquid may enter the drain body 55 therebelow. A feature of my structure consists in the provision of a substantially continuous peripheral slot between the perforate body of the grate and the rim 6 of the drain body. In Figs. 1 and 2 such slot is indicated at 9, formed by and between the outer edge 12 of the body 60 of the grate and the inner edge 14 of the drain body rim 6.

65

70

Extending outwardly from the grate body is a plurality of relatively narrow radial lugs 15 that are widely spaced apart circumferentially of the grate, so that the slot 9, as far as flow of drainage liquid into the drain is concerned, forms a substantially continuous flushing opening which is peripherally coextensive with the down-sweeping wall of the drain structure. The lugs 15 engage the side wall portion *f* of the upper drain body portion or collar 4, which portion *f* forms an annular, downwardly sloped seat for the grate 7. A large part of any liquid to be drained from surface 8 is received by the slot 9, whence the liquid flows straight downwardly upon and over the unrestricted internal surfaces of the drain body below, thereby flushing such surfaces with a down-sweeping flow of liquid that keeps them clean. While the slot 9 is narrow enough to exclude from the drain solids of a size that might clog the drain pipe, the area of said slot is so proportioned with respect to the aggregate area of the openings between the bars 13 that, as noted, a large part of the liquid draining into the structure enters by way of the slot, thus insuring the desired scavenging or scouring flow of liquid downward upon the unrestricted drain body side wall.

If it is desirable to flush-out the drain pipe, and the trap associated therewith, with a bucket of water or a hose, it is not necessary, as in the case of prior structures, to remove the grate, since an adequately rapid flow of water through the drain can be obtained to remove sediment from the drain pipe and trap, if indeed sediment can collect when the drain of this invention is used. My drain structure serves substantially the same purpose as the more costly flushing rim drains that are provided with a hollow rim into which water is piped under pressure. Furthermore, the tapping of such flushing water from city supply lines is undesirable because it necessitates cross connections with the city supply, with the danger of back siphonage and contamination of the city water.

Another point may be mentioned. Since the grate 7 is supported by lugs located outward from the grate rim 12, the tendency is negated for the grate to tilt when pressure or load is applied to the rim of the grate. Indeed, the grate tends to seat tighter and to be more resistant to tilting when load is applied to its rim, located as it is within the limits of the points of support. If desired, certain of the lugs 15 may be secured by means of screws 16 passed through the lugs into threaded engagement with bosses 17 integral with drain body portion 4.

The outwardly extending radial lugs not only support the grate on the drain body, but space the grate and its rim from the wall of the drain body.

The particular form of the drain body may be varied in many ways, but the feature of my present invention is illustrated in Fig. 3 wherein the upper body portion 4a of the adjustable drain body is formed of a relatively inexpensive rough-finish material, such as cast iron, and has an integral peripheral edge or rim that is modified to receive a separately formed renewable finish rim device of a relatively expensive "high-finish" material such as brass, bronze, chrome, etc., in the form shown at 18, the upper edge of the adjustable drain body portion 4a being chamfered or downwardly and inwardly inclined from a feather edge to form a seat 19, and being rabbeted at 20 to engage the correspondingly shaped finish rim 18. At four points, more or less, in the circumferential extent of the rim 18, countersunk holes are provided for grate-securing screws 21, and at these points drilled and threaded lugs 22 are provided on the adjustable drain body to receive the screws. The grate 24 may be formed of the same relatively costly "high-finish" metal as the renewable rim 18, and the lugs 23 of the grate, otherwise formed as the lugs 15 of the grate 7 of Figs. 1 and 2, are extended downward below the body proper of the grate to engage

the seat 25 on the drain body. Such downward extension of the lugs 23 permits the grate body proper to be of less vertical depth and of lighter weight than would be the case if the grate were of the same depth as the lugs.

Fig. 4 illustrates a modification, where the upper body or collar portion 4b of the drain body is formed of a rough-finish material, such as cast iron, and is adapted to receive a renewable finish rim 26. The top or top surface of the drain body rim has a tapered and feather-edged seat 27, and the renewable finish rim is similarly tapered across its entire under surface, to engage snugly upon the tapered seat 27. The renewable rim 26 is a separate or independently formed element, removably secured to the rim of the drain body by means of a suitable number of screws 28 that are received in drilled and threaded bosses 29 cast integrally with the drain body portion 4b. The grate 30 is essentially the grate 7 described, save that grate 30 may be formed of the same "high finish" metal as the rim 26. The grate-supporting lugs 31 are extended below the body of the grate to engage the relatively deep seat 32 without necessitating a heavy or thick grate structure. Bosses 33, cast integrally with the drain body and fitted with drilled and threaded brass bushings 34, receive grate-securing screws 35 that extend through lugs 31, it being noted that only one of the lugs 31 appears in Fig. 4.

In the structure of Figs. 5 and 6 the drain body may be formed of the same material as the drain bodies already described, and the renewable finish rim portion 48 comprises a separate or independently formed element seated at 48b upon the rim 42d of the drain body. This renewable finish rim is provided with an annular portion 48a that extends downwardly adjacent to the inner surface of the drain body side wall, as shown in Fig. 6, with the inner side face or surface of portion 48a substantially aligned vertically with the internal side surface of the drain body immediately therebelow. It will be understood that in Figs. 5 and 6, as in the case of the structures of Figs. 3 and 4, the outer peripheral edge of the drain body rim or top edge and the outer peripheral edge of the renewable finish rim comprise feathered edges that meet in a line or seam 48g lying substantially in the plane of the surface to be drained. At its lower edge the rim portion 48a carries a plurality of horizontal lugs 48c that are widely spaced around the circumference of the drain, as will be understood upon reference to Fig. 5. Two or more of the lugs 48c are provided with screws 48d that are secured in threaded engagement with bosses 42s formed integrally with the drain body, whereby the renewable finish rim is removably secured to the drain body. The grate 46 of the modified structure of Figs. 5 and 6 is provided with cross bars 46c and radial lugs 46d that seat upon and cover the lugs 48c of the renewable rim 48, and the circumferential flushing slot 110 of the drain is formed by and between the inner edge 48f of the renewable rim and the outer edge 46e of the body of grate 46. A bolt 46h is arranged to secure the grate in seated position. In order to facilitate the positioning of the grate 46 with its lugs 46d in registry with the lugs 48c of the rim 48, the said rim 48 is provided with one or more notches 80c, Fig. 5, and a corresponding number of the lugs of the grate are extended, as at 60c, to fit such notches. Screws 48e engage the lugs 60c to lugs 48c. Either the rim 48 or the grate 46, or both the rim 48 and the grate 46, may be readily removed from the drain installation for renewal, refinishing or interchange with other rims or grates, all without marring the adjacent surface of the floor in which the drain is installed.

As shown in Figs. 3, 4 and 6, the body of the integral rim is extended externally a substantial interval vertically downward from the feather edge of the rim, cf. 42d in Fig. 6, to provide a rim of substantial vertical thickness and to afford a permanent and rigid assembly with the

floor structure, and to insure peripheral strength beneath the inclined seat for the renewable finish rim.

It may be noted that separately formed renewable finish rims of the sort described herein, permit the use of various forms of grates, perforated or solid covers, or flat and dome-shaped grates or covers. Also, the use of renewable finish rims may in certain cases allow the permanent or periodic discard of grates, without danger of the drain body being damaged.

Various other modifications of the structure described may be made without departing from the spirit of the invention defined in the appended claims. In all of the renewable rims disclosed in this case, it will be perceived that the top edge of an inexpensive cast iron drain body is entirely covered by a highly finished rim of attractive appearance, and, as distinguished from all prior art of which I have knowledge, the tapered or beveled meeting surfaces of the top edge of the drain body and the outer edge of the renewable rim applied thereto terminate at their outer peripheries in feather edges precisely in a fine joint or seam that lies in the plane of the surface to be drained, whereby the rim may be removed, and replaced or renewed, without marring the tile or other finish of the surface of the floor in which the drain structure is installed. As shown, the bottom surface of each of my renewable rims is complementary in form to the top surface or surfaces of the rim or top edge of the drain body which it removably engages, and the top surface of each renewable rim lies flush with the surface of the floor to be drained. All portions of the renewable rim are free from overlapping engagement with the floor. A specific and valuable contribution to the art is realized in this invention.

The application for these Letters Patent comprised a continuation in part of my copending application Serial No. 356,748, filed May 22, 1953, now abandoned.

I claim:

1. In a surface drain of the character described, in

combination, an open ended hollow body formed of relatively inexpensive rough-finish material for installation in a floor structure, the top of said body terminating in an annular integral rim, said rim having on its upper face an inner annular downwardly and inwardly extending seat, said seat having at its outer periphery a feather edge to be disposed in the plane of the surface of the floor structure, said body rim having an outer peripheral surface which extends downwardly into and is assembled with the floor structure, an annular finish rim of high-finish rigid material mounted on said body rim seat independently of said floor surface structure, said finish rim having an upper peripheral surface coinciding with the peripheral face of said body rim seat and a bottom surface conforming to and covering said body rim seat, a grate closing said body opening at the level of the floor surface and supported within said finish ring and means for removably securing said finish rim upon the integral rim of the body.

20 2. The surface drain as defined in claim 1 wherein the grate is disposed wholly within the plane of the upper face of said finish rim and supported thereon.

25 3. The surface drain as defined in claim 1 wherein grate seating means are provided within said drain body below said finish rim and a grate is disposed wholly within the plane of the upper face of said finish rim and supported on said grate seating means.
